UNITED STATES PATENT OFFICE

2,556,708

HYDRAULIC CIRCUIT APPARATUS

Lutwin C. Rotter, Maplewood, and Victor G. Klein, St. Louis, Mo., assignors to Lincoln Engineering Company, St. Louis, Mo., a corporation of Missouri

Original application March 13, 1944, Serial No. 526,160, now Patent No. 2,399,573, dated April 30, 1946. Divided and this application April 16, 1945, Serial No. 588,452

3 Claims. (Cl. 277—20)

1

This invention relates to hydraulic circuit apparatus, and with regard to certain more specific features, to high-pressure apparatus of this class.

The invention is a division of the invention described in our United States Patent 2,399,573 dated April 30, 1946, for Hydraulic Circuit Apparatus.

Among the several objects of the invention may be noted the provision of hydraulic apparatus and the hydraulic circuit formed thereby for commercially producing extremely high unit pressures (for example 25,000 p. s. i.) for hydraulic testing purposes, and liquid supplies for hydraulic presses, hydraulic machine tools and the like; the provision of apparatus and a circuit of the class described which will quickly produce said pressures in cases where high bulk factors exist in the apparatus requiring the pressures; the provision of apparatus of this class which will hold the stated high pressure indefinitely even with leakage in the apparatus served; and the provision of means of the class described which is reliable, compact, safe and foolproof, and which will remain so over a long life. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a side elevation of apparatus embodying the invention;

Fig. 2 is an enlarged top plan view of Fig. 1;

Fig. 3 is a fragmentary front elevation (viewed from the right of Figs. 1 and 2) drawn on the scale of Fig. 2;

Fig. 4 is an enlarged, detailed plan view of a valve control block, being viewed substantially from line 4—4 of Fig. 3;

Fig. 5 is a horizontal section through said control block, being taken on line 5—5 of Fig. 3;

Fig. 6 is a left-side elevation of Fig. 4, being viewed from line 6—6 of Fig. 4;

Fig. 7 is a horizontal sectional view of a control valve, being taken substantially on line 7—7 of Fig. 3;

Fig. 8 is a vertical section taken through a high-pressure pump element, the section being taken on line 8—8 of Fig. 3;

Fig. 9 is an enlarged detail section of an outlet

2

check valve assembly for a high pressure pump; and,

Fig. 10 is a circuit diagram.

Similar reference characters indicate corresponding parts throughout the several views of the drawings.

The hydraulic system and apparatus of the present invention are adapted commercially to produce a high working pressure (up to 25,000 p. s. i.) operating from a low pressure air supply (of the order of 100 p. s. i.). This end is attained without any substantial danger of explosion and at high volumetric capacity.

Referring now more particularly to Figs. 1—3, there is shown at numeral 1 a framework supporting a tank 3. The latter carries liquid up to a level such as shown at L in Fig. 3. The exact level is not important, since it is primarily the measure of the amount of fluid carried in the tank (40 lbs., for example). The liquid may be oil or light grease. At the bottom of the tank is an outlet connection 5 which through a T 7 has one branch 9 leading to a solid steel high-pressure distributor and control block 11. The other branch of the T 7 leads to a drain cock 13 which is normally closed but which may be opened for drainage and charging of the tank, and for removing sedimentation of solids, or moisture due to condensation.

Above the liquid level L the tank 3 carries air, an inlet 15 being provided for its introduction. This inlet is connected by a branch pipe 19 to an air header 17. Another branch 21 leads from the header 17 to the inlet of a first reciprocating air engine 23. A third branch 25 from the header 17 leads to a second reciprocating air engine 27. In the branch line 25 is a manually controlled regulator valve 29 and a suitable pressure gauge 31.

The header 17 receives its air through a three-way valve 33 from an air inlet line 35. The air line 35 carries air pressure at, for example, 100 p. s. i. pressure. This is an ordinary valve available from many air compressor supply companies. The valve 33 (Figs. 3 and 7) has an exhaust outlet 37 and a rotary plug 39 in which is a three-way port 41. Plug 39 is operated by handle 40. In the position of the valve plug shown in Fig. 7 air may pass from the supply pipe 35 to the header 17. By rotating the plug 90° counter-clockwise, the air supply may be cut off and the header 17 connected with the exhaust 37. Thus by opening the valve 33 air may be supplied to the tank 3 above the liquid therein at 100 p. s. i. It is also supplied at that same pressure to the

first air engine 23 and to the second engine 27 at that or a lower pressure, as determined by the regulator 29.

Each air engine 23 and 27 is of the general type disclosed in United States Patents 2,215,852 and 2,269,423, dated September 24, 1940 and January 13, 1942, respectively. Further description it is believed will be unnecessary in view of the showing in these patents, except to state (see Fig. 10) that engines 23 and 27 have reciprocating, double-acting, air-operated pistons 24 and 28 respectively to which air is distributed for double action by means of valve gears 43 and 44 respectively. The total pressure exerted by each piston under a given air pressure is proportional to its area. The area of the piston of engine 23 is smaller than that of the piston of engine 27.

The piston 24 of engine 23 is connected to the plunger 16 of a well type of hydraulic pump indicated broadly at 45. The pump 45 extends down to a point near the bottom of the tank 3, where it has its inlet check valve 18 always submerged for all normal variations in the level L. Associated with plunger 16 is a valve 20. Pumps of this class operated by air engines similar to 23 are known and will not be further described (see, for example, United States Patent 1,970,591, dated August 21, 1934). The outlet of the pump is indicated at 49. This outlet is connected by means of pipe 51 with the control block 11. The piston of air engine 27 is connected to the piston of a hydraulic booster pump indicated broadly at 47, the details of which are shown in Fig. 8.

Details of the control block 11 are shown in Figs. 4-6. It consists of a solid steel piece in which is an outlet manifold 53 to which is connected an outlet pipe or service connection 55. This pipe 55 is connected with the device or machine to which liquid pressure and volume are to be supplied, which may be a device to be tested for high pressure, or a hydraulic press or other machine. This control block has an inlet passage 57 to which is connected the line 9 leading from the liquid tank 3. In a cross passage 61 is a new type of check valve 59 especially adapted to the high pressures involved.

Valve 59 consists in a cylindric counterbore 63 in passage 61, at the bottom shoulder 65 of which counterbore is seated a disc 67 having openings 69. This disc is recessed as shown at 71 for producing a ledge 73. This ledge 73 provides the seat for the endmost of a series of accurately made ring seats 75, each of which seats endwise on another and each of which has an interior conical opening or chamber 77 rounded at its small end as shown at 79. Accurately seating balls 81 are carried within the conical openings 77, separated from one another when seated. These, under unbalanced pressure from 53 to 57 rest upon the seats. Under unbalanced pressure from 57 to 53, they unseat and form a stock in contact. A gland nut 83 serves to press together disc 67 and the ring seats 75. Nut 83 is counterbored as indicated at 85 and provided with openings 87 to the counterbore so that fluid may flow from inlet 57 through the valve 59 to the outlet 55, unseating the balls 81 as it does so. However, the balls are prevented from escaping by the disc 67. The space between the endmost ball and the disc 67 is less than the movement of the balls which would bring about reclosing of the balls on the rounded ends 79 when opened.

Passing through the nut 83 is a threaded, rotary, operating stem 89, packed as indicated at 91 and having a nose portion 93 which may contact

the lowermost one of the balls 81. A cross pin 95 prevents the stem 89 from being unthreaded too far. Outside, the stem 89 carries a crank handle 97 and between it and the nut 83 is a tubular spacer 99 which permits the operator to screw the stem forward only enough to cause unseating of the balls 81 without pressing the endmost one into engagement with member 61.

The counterbore 63, disc 67, ring seats 75 and balls 81 are made to a high degree of accuracy including lap fits where necessary to prevent leakage. The balls and the conical seats 77 are arranged so that upon closing the valve the upper ball seats first, then the second, third and fourth successively. Upon opening the valve the lowermost ball opens first and then the others in serial order, the uppermost opening last. The advantage of such a construction is that as the endmost ball comes to a seat under high pressure, all of them gradually exert increased throttling action without all seating at once. This reduces the cutting action of fluid in passing between the balls and the seats. When the balls open, the upper one unseats last, the others having already opened in serial order.

At numeral 101 is shown another valve similar to the one just described in which like numerals designate like parts. The holding nut 103 for this valve differs from the nut 83 in that it has no operating stem through it. This valve 101 is in a passage 105 which leads to the outlet manifold 53.

A passage 107 is connected through the openings 87 to the inside of the nut 103. It is this passage 107 on the inlet side of the valve 101 to which is connected the pipe 51 from the pump 45. This passage 107 is also connected by means of a pipe 109 to the inlet 111 of the booster pump 47 above-mentioned (Fig. 8). The plunger 40 of this pump is shown at 113 and is connected with the piston 28 of the reciprocating air engine 27.

The outlet 115 of the pump 47 is connected to the outlet passage 53 in the block 11 and provides a high-pressure inlet to the block. A special outlet check valve 117 is used in pump 47 and consists in a threaded thimble 119 counterbored as shown at 121 to receive a series of closely dimensioned rings 123 having oppositely countersunk openings 120 therethrough. Balls 125 are trapped in the spaces left by the countersinks and seat on the bottoms of openings 120 in a direction to allow flow from the pump but to resist back flow of fluid to the pump. Milled slots 59 prevent the balls from seating on the upper ends of openings 120 when flow is from recess 126. Each ring has a ledge 122 at one end for telescoping with a shoulder 124 of its neighbor. Copper packing washers 131 are used between the ledges 122 and shoulders 124. The last ring toward the pump telescopes recess 126 and seats on a copper washer 128. The last ring in the other direction seats on a copper washer 128 in the bottom of the counterbore 121. Axial pressure from threading home the thimble 119 seals together all of the rings 123.

Fig. 10 will aid in following the operation which is as follows, assuming that the tank 3 has been filled up to the level L with suitable liquid. Crank 97 is backed off from the position shown in Fig. 5 to allow valve 59 to operate automatically. The necessary connection with the apparatus to be supplied with pressure is made through line 55. Air at 100 p. s. i. or so is supplied from the pipe 35 and the valve 33

is opened as indicated in Figs. 7 and 10. This supplies air at 100 p. s. i. on the surface of the liquid in the tank 3. It also supplies air at this pressure to the air engine 23 and air under pressure to the engine 27. The regulator 29 is set for an air pressure which when operating on the booster pump 47 will produce the ultimate hydraulic pressure desired in line 55.

Pressure of air on the liquid in the tank 3 quickly forces it out in volume to the inlet 57 of the block 11. The pressure automatically opens the valve 59 and flow occurs through the outlet manifold 53 to the supply line 55. This quickly fills the apparatus to be tested even though it has a high bulk factor. This is because the displacement of air into tank 3 and displacement of liquid therefrom may be quite fast.

At the same time the engine 23 starts automatically due to the air pressure supplied to it. This reciprocates the pump 45 which draws fluid from the bottom of the tank and forces it out through the line 51. Thus it is delivered to port 107 in the block 11, from whence it passes through the check valve 101 to the outlet 53 and also to the line 55.

When, due to filling up of the apparatus connected with 55, the reaction pressure in the pipe 55 becomes greater than the unit pressure on the liquid in the tank 3 (100 p. s. i.), the valve 59 automatically closes and the pump 45 continues to supply pressure through the valve 101. The pump 45 and engine 23 are capable (for example) of running the pressure up to 2,000 p. s. i. Pump 45 may be considered to be a primer pump. The pressure of 2,000 p. s. i. is determined by the relative areas of the engine piston and pump plunger.

During the operating period above described, the engine 27 has also received air and has been operating its pump 47 which supplies fluid at the connection 115 of the block 11. Thus this pump 47 also supplies fluid to the outlet manifold 53 and hence to the pipe 55. The pump 47 receives its supply from the primer pump 45 via pipe 51, port 107, line 109 and port 111. The area of the piston in engine 27 and the area of its pump plunger are so related that pump 47 generates about 25,000 p. s. i. hydraulic pressure. Thus, as the reaction pressure in line 55 builds up past the 2,000 p. s. i. value of pump 23 the valve 101 also closes and thereafter the pipe 51 from pump 45 supplies only the pump 47 via line 109. Pump 47 at all times acts as a booster pump for the primer pump 45. Thus the pump 47 continues to build up pressure, both valves 59 and 101 being closed, until the pressure in the line 55 reaches the stated value of about 25,000 p. s. i. The exact value is determined by the setting of the regulator 29 which controls the unit air pressure applied to the piston of the engine 27.

At this point it will be clear why the valves 59 and 101 need to be of improved construction. No ordinary check valve would be able to last long under a pressure difference between 25,000 p. s. i. in the manifold 53 and the 100 p. s. i. in the port 57 (in the case of valve 59); nor the pressure difference between 25,000 p. s. i. and the 2,000 p. s. i. in the port 107 (in the case of valve 101).

The engines 23 and 27 automatically stop when the pumps 45 and 47 respectively reach pressures of 2,000 p. s. i. and 25,000 p. s. i. For example, the ratio of areas of the pistons in engine 23 and pump 45 is 20:1, thus producing from 100 lbs. air pressure approximately 2,000 p. s. i. In the case

of the booster engine 27, the ratio of its piston area to the area of the plunger 113 in pump 47 is 370:1 which gives a margin for adjusting down the air pressure at regulator 29 and still obtaining 25,000 p. s. i. or better in the outlet of pump 47. When the pumps stall (as they will when their plunger pressures balance the respective air engine pressures), the high pressure will be maintained in the outlet 55 even though leakage should occur. This is because as soon as the outlet pressure drops, this unbalances the hydraulic pressure with respect to the air pressure on the piston of engine 27 whereupon the latter again starts to bring the hydraulic pressure back up. When engine 27 starts, engine 23 also starts because the requirements of pump 47 incipiently drop the pressure in line 51.

Upon completion of a testing or operating cycle, the three-way air valve 33 is moved to its exhaust position, thus exhausting air from the pressure tank and from the engines 23 and 27. The crank 97 is then rotated to the position shown in Fig. 5 against the limiting stop 99. This opens the check valve 59 and hydraulic fluid bleeds back through the check valve 59 and returns to the pressure tank.

The present invention is an improvement over prior schemes for the purpose, since it introduces an intermediate-pressure filling operation after a low-pressure filling operation and before the highest pressure is applied. Thus not only does it take care of bulk factor due simply to the requirements of bulk factor (due to stretching under substantial pressure) of the physical parts of the system, including the apparatus served. Loss of time is avoided that would be involved in taking up the last-mentioned bulk factor by means of the high-pressure application. In other words, the air pressure in tank 3 quickly causes filling of the system, the intermediate-pressure primer pump quickly stretches the physical parts of the system under the 2,000 lbs. pressure, and the booster pump completes the high-pressure application. If the higher-pressure booster pump 47 were to operate alone throughout the pressure range that the intermediate-pressure pump now does, the time required for a cycle of operation would be much longer due to the necessarily low volumetric displacement of pump 47.

The apparatus is safe, since no pressures higher than 100 p. s. i. or so are applied to the tank 3.

It is to be understood that, although air pressure is used, other gases under pressure may be employed and the terms air and gas are to be understood as being synonymous. Also other liquids besides oil may be employed, such as hydraulic brake fluid, water, alcohol, all being equivalents for the purpose of the invention.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. High-pressure hydraulic apparatus comprising a pressure block, said block having an outlet manifold and a low-pressure inlet passage connected thereto, a first check valve connecting said inlet passage with said outlet manifold, said check valve opening only downstream from the inlet

passage to the outlet manifold, a second intermediate-pressure inlet having a connection with said outlet manifold, a second check valve in said last-named connection, a second intermediate-pressure outlet communicating with said second inlet, and a third high-pressure inlet connected with said outlet manifold, said third inlet being with respect to said second inlet on the downstream side of said second check valve.

2. High-pressure hydraulic apparatus comprising a pressure block, said block having an outlet passage and a low-pressure inlet manifold connected thereto, a first check valve connecting said inlet passage with said outlet manifold, said check valve opening only downstream from the inlet passage to the outlet manifold, a second intermediate-pressure inlet having a connection with said outlet manifold, a second check valve in said last-named connection, a second intermediate-pressure outlet communicating with said second inlet, and a third high-pressure inlet connected with said outlet manifold, said third inlet being with respect to said second inlet on the downstream side of said second check valve, said second outlet and third inlet being connected by a 25 passage located outside of the block.

3. High-pressure hydraulic apparatus comprising a pressure block, said block having an outlet manifold and a low-pressure inlet passage connected thereto, a first check valve connecting said inlet passage with said outlet manifold, said check

5
